UNITED STATES PATENT OFFICE.

GEORGE E. BATES, OF ORION, MICHIGAN.

SHOULDER-BRACES.

SPECIFICATION forming part of Letters Patent No. 733,897, dated July 14, 1903.

Application filed January 2, 1903. Serial No. 137,420. (No model.)

To all whom it may concern:

Be it known that I, GEORGE E. BATES, a citizen of the United States, residing at Orion, county of Oakland, State of Michigan, have 5 invented a certain new and useful Improvement in Shoulder-Braces, of which the following is a specification, reference being had to the accompanying drawings, which form a part of this specification.

10 My invention has for its object certain new and useful improvements in shoulder-braces; and it consists of the construction, combination, and arrangement of devices hereinafter described and claimed, and illustrated in the 15 accompanying drawings, in which—

Figure 1 is a view in perspective, showing the parts arranged as when in use. Fig. 2 is a view of the same, showing the forward ends of the side tension-straps detached. Fig. 3 is 20 an edge view showing the end of a shoulder-strap with the devices attached thereto.

The object of my invention, more particularly, is to provide improved shoulder-braces of simple construction, the braces not only 25 acting as braces, but serving also as suspenders for carrying the clothes, various parts being readily adjustable, as more especially hereinafter set forth.

I carry out my invention as follows:

30 Right and left hand shoulder-straps are indicated, respectively, at *a* and *b* and right and left tension-straps at *c* and *d*. The right shoulder-strap *a* and the left tension-strap *d* are formed in a single piece of webbing or 35 other suitable material, while the left shoulder-strap *b* and the right tension-strap *c* are also formed in a single piece. The two pieces *a* *d* and *b* *c* cross each other at the back, as indicated at *e*, between the shoulders at es- 40 sentially right angles. The two shoulder- straps *a* and *b* are passed through metallic loops (indicated at *f* and *g*) toward their forward ends and are provided at their extremities with sliding buckles *h* and *i*, through 45 which the corresponding shoulder-straps are also passed and whereby the respective shoulder-straps may be adjusted as to length in a common manner. Attached to the loops *f* and *g*, respectively, are front suspender-straps 50 *j* and *k*, the upper extremities thereof being passed through the corresponding loops *f* and *g* and secured in place preferably by stitch-

ing. The opposite extremities of the front suspender-straps *j* and *k* are passed through suitable buckles, (indicated at *n* and *p*,) preferably consisting of what are known as "wire buckles," each formed with a hook, upon which are engaged a tube and ring, (indicated at *q* and *r*,) front suspender-ends *s* and *t* being engaged through said tubes in the customary manner. It will be seen that by the employment of the sliding buckles *h* and *i* and the sliding buckles *n* and *p* a double adjustment is provided at the front, the right and left shoulder-straps being adjustable as 60 to length by means of the sliding buckles *h* and *i* and the corresponding suspender-ends being adjustable upon the suspender-straps by means of the buckles *n* and *p*. This provision for double adjustment of the length of 65 these corresponding parts is deemed to be a feature of special importance and utility. The right and left hand tension-straps *d* and *c* are provided at their free or lower ends with sliding buckles, (indicated at *u* and *v*,) said buckles 70 preferably consisting of the well-known wire buckles, each provided with a hook 7 and a clasp 8 to be forced down upon the hook. The hook 7 may be engaged with the corresponding metallic loops *f* and *g*. By 75 means of said buckles *u* and *v* the tension of the straps *d* and *c* may be adjusted as may be required, said buckles *u* and *v* being adjustable upon the corresponding tension-straps. The buckles *u* and *v* are made to 80 have a detachable engagement with the corresponding loops *f* and *g*, the hooks of the buckles *u* and *v* being detachably engaged in the adjacent ends of the corresponding metallic loops, the ends of the shoulder-straps 85 being passed through said loops, as described, 90 permitting the ready engagement of the hooks of the buckles *u* and *v* with the corresponding loops and their ready disengagement therefrom, as the material of said shoulder-straps is not closely engaged over the corresponding loops. The buckles *u* and *v* might, however, be engaged, if preferred, 95 with the buckles *n* and *p* or with the rings of the devices *q* and *r* instead of with said loops, 100 if preferred.

The back suspender-strap is indicated at *w*, the upper end of which is located between the straps *a* *d* and *b* *c* at their intersection

and may be stitched thereto. At its lower end the strap *w* is provided with a sliding buckle *x*, preferably an ordinary wire buckle, provided with a hook upon which are secured 5 a tube and ring *y*, through which are passed suspender-ends *z*.

It will be perceived that the various suspender-ends above described are thus detachably engaged with the corresponding 10 sliding buckles upon the corresponding suspender-straps, the rear suspender-ends being detachably engaged with the rear strap *w*, as well as the front suspender-ends being detachably engaged with the buckles upon the 15 front suspender-straps *j* and *k*.

It will be seen that where the straps *a d* and *b c* cross each other at the back the parts are flat and smooth, no metallic devices being used thereto. The back suspender-strap *w* 20 has thus an adjustable engagement with the corresponding buckle *x* thereupon, so that its length may be adjusted as required.

It will be seen that all of the adjustments for tension as a shoulder-brace are at the 25 sides in front. This construction and arrangement make the adjustment of the tension portions of the brace readily accessible, and therefore the adjustments may readily be made.

30 A special feature of my invention is to secure a double adjustment at the front of the shoulder-braces, which I secure, as above described, by means of the sliding buckle on the end of each of the shoulder-straps and the 35 sliding buckle on the end of each of the suspender-straps. The upper adjustment—*i. e.*, the adjustment provided for by the sliding buckle on the end of each of the shoulder-straps—is to bring the metallic loop higher or 40 lower in order that the corresponding tension-strap at its extremity may be raised or lowered, so as to carry the tension-straps nearer to or farther away from the armpit, as may be required. Afterward the sliding buckles on 45 the lower ends of the suspender-straps may be adjusted to make the suspender portions of the device of required length, or, in other words, to give the brace the proper length for use as suspenders. While I have described 50 hereinbefore means for securing this double adjustment at the front of the braces, I do not limit myself solely to these particular means for securing this object, but hold myself entitled to such variations and modifications as 55 come within the spirit of my invention.

It will be seen that the forward ends of the shoulder-straps *a b*, the front suspender-straps *j k*, and the suspender-ends *s t* attached thereto form front suspender portions 60 of the brace.

It will be seen that the suspender-ends are 65 adjustably connected with the suspender-straps independently altogether of the means for adjusting the connection of the tension-straps with the shoulder-straps. Were it not for this provision for independent adjustment of the sliding buckles on the lower ends of

the suspender-straps, it will readily be seen that any vertical adjustment of the tension-straps in their engagement with the shoulder-straps would lengthen or shorten the suspender portions of the device. It will also be seen that the tension-straps are detachably engaged at their forward extremities with the front suspender portions of the brace, the 70 tension-straps having at their forward extremities both a detachable and a vertically-adjustable engagement with the front suspender portions of the brace, means being provided adjustably engaged with the forward extremities of the tension-straps whereby the tension-straps may have a vertically-adjustable engagement with the shoulder-straps. It is obvious that by detaching the tension-straps the remaining features of the 85 device still serve as a suspender.

A separate and distinct adjustment as to length of the suspender portions of the brace and of the suspender-ends, together with the adjustment provided for the tension-straps, 90 render it possible to keep the tension-straps at any desired distance from the armpit, while at the same time and by the same means the suspender portions of the device and the suspender-ends may be adjusted as to length 95 to any extent required.

What I claim as my invention is—

1. A shoulder-brace comprising shoulder-straps, front suspender-straps, front suspender-ends, a rear suspender-strap, and rear suspender-ends adjustable upon the rear suspender-strap, said shoulder-straps being adjustable at their forward ends as to length, and said front suspender-ends having an additional vertical adjustment upon the front 105 suspender-straps.

2. A shoulder-brace comprising shoulder-straps provided at their forward ends with loops through which the corresponding front ends of the shoulder-straps are passed, devices adjustably connecting the ends of the shoulder-straps with the body of the straps whereby the shoulder-straps are adjustable as to length, front suspender-straps engaged with said loops, front suspender-ends having a vertically-adjustable engagement upon the suspender-straps, and a rear suspender-strap. 115

3. A shoulder-brace comprising shoulder-straps adjustable at their forward ends as to 120 length, front suspender-straps, front suspender-ends adjustable upon the front suspender-straps, and tension-straps, the tension-straps detachably engaged at their forward extremities with the front suspender 125 portions of the brace.

4. A shoulder-brace comprising shoulder-straps, front suspender-straps, front suspender-ends, tension-straps, and a rear suspender-strap, the shoulder-straps at their forward ends being adjustable as to length, the front suspender-ends having a vertically-adjustable engagement with the front ends of the suspender-straps, and means adjustably 130

engaged with the forward extremities of the tension - straps whereby the tension - straps may have a vertically-adjustable engagement with the shoulder-straps.

5. A shoulder-brace comprising shoulder-straps, suspender-straps, front and rear suspender-ends, tension-straps, means for securing an adjustment as to length of the front portions of the shoulder-straps, and means for securing an additional adjustment of the front suspender-ends upon the suspender-straps.

6. A shoulder-brace comprising two straps intersecting at the back, each comprising a shoulder-strap and a tension-strap, front and rear suspender-straps, front suspender-ends having a double vertical adjustment with the forward extremities of the shoulder-straps, and means whereby the forward ends of the tension-straps may have a detachable and vertically - adjustable engagement with the front suspender portions of the device.

7. A shoulder-brace comprising two straps intersecting at the back, each forming a shoulder-strap and a tension-strap, metallic loops through which the forward ends of the shoulder-straps are passed, sliding buckles upon the forward extremities of the shoulder-straps whereby the forward ends of the shoulder-straps may be adjusted as to length, suspender-straps engaged with said loops, and suspender-ends having an independent vertically-adjustable engagement with said suspender-straps.

8. A shoulder-brace having in combination two straps intersecting at the back, each comprising a shoulder-strap and a tension-strap, metallic loops through which the forward ends of the shoulder-straps are passed respectively, sliding buckles engaged with the forward extremities of the shoulder-straps, a sliding buckle upon the extremity of each tension-strap having a detachable engagement with the corresponding loops, a suspender-strap engaged with each of said loops, a sliding buckle upon the lower end of each of said suspender-straps, a suspender-end engaged with each of the sliding buckles upon the suspender-straps, and a rear suspender-strap engaged with the two first-mentioned straps.

9. A shoulder-brace having in combination two straps intersecting at the back, each comprising a shoulder-strap and a tension-strap, metallic loops through which the forward ends of the shoulder-straps are passed respectively, sliding buckles engaged with the forward extremities of the shoulder-straps, a sliding buckle upon the extremity of each tension-strap having a detachable engagement with the corresponding loops, a suspender-strap engaged with each of said loops, a sliding buckle upon the lower end of each of said suspender-straps, a suspender-end engaged

with each of the sliding buckles upon the suspender-straps, and a rear suspender-strap 65 stitched to the intersecting portions of the two first-mentioned straps.

10. A shoulder-brace having in combination two straps intersecting at the back, each comprising a shoulder-strap and a tension-strap, 70 metallic loops through which the forward ends of the shoulder-straps are passed respectively, sliding buckles engaged with the forward extremities of the shoulder-straps, a sliding buckle upon the extremity of each tension-strap having a detachable engagement with the corresponding loops, a suspender-strap engaged with each of said loops, a sliding buckle upon the lower end of each of said suspender-straps, a suspender-end engaged 80 with each of the sliding buckles upon the suspender-straps, and a rear suspender-strap stitched to the intersecting portions of the two first-mentioned straps, a sliding buckle upon the lower end of the rear suspender-strap, and suspender-ends engaged with the buckle upon the rear suspender-strap.

11. A shoulder - brace comprising a right shoulder-strap and a left tension-strap formed in a single piece, a left shoulder-strap and a 90 right tension-strap formed in a single piece and intersecting the right shoulder-strap and left tension-strap at the back, metallic loops through which said shoulder-straps respectively are passed toward their forward ends, 95 a sliding buckle adjustably engaged with the forward extremity of each of the said shoulder-straps, a sliding buckle adjustably engaged with the extremity of each of said tension-straps and having a detachable engagement with the corresponding loop, a suspender-strap engaged with each of said loops, a sliding buckle adjustably engaged with the extremity of each of said suspender-straps, suspender-ends engaged with the sliding buckles upon the suspender-straps, a rear suspender-strap stitched to the intersecting portions of the shoulder - straps and tension-straps, a sliding buckle adjustably connected with the rear suspender-strap, and suspender-ends engaged with the buckle upon the rear suspender-strap.

12. Shoulder-braces comprising shoulder-straps adjustable as to length, front suspender-straps engaged with the shoulder-straps, front suspender-ends adjustable upon the suspender-straps, and tension-straps adjustable as to length engaged with the forward suspender portions of the device.

In testimony whereof I have signed this 120 specification in the presence of two subscribing witnesses.

GEORGE E. BATES.
